(57) **CLAIM**

The ornamental design for a hydraulic driven rotary tool, as shown and described.

DESCRIPTION

FIG. 1 is a perspective view of the tool;

FIG. 2 is a left side elevational view of the tool;

FIG. 3 is a right side elevational view of the tool;

FIG. 4 is a front elevational view of the tool;

FIG. 5 is a rear elevational view of the tool;

FIG. 6 is a top plan view of the tool; and,

FIG. 7 is a bottom plan view of the tool.

The broken lines illustrate portions of the hydraulic driven rotary tool that form no part of the claimed design.
